[57] **CLAIM**

The ornamental design for a table, substantially as shown and described.

DESCRIPTION

FIG. 1 is a top plan view of a table showing my new design:

FIG. 2 is a front elevational view thereof;

FIG. 3 is a bottom plan view thereof;
FIG. 4 is a top plan view of a first alternate embodiment of a table showing my new design;

FIG. 5 is a front elevational view of the first alternate embodiment; and

FIG. 6 is a bottom plan view of the first alternate embodiment.

The right and left side elevational views of the table are substantially identical to the front elevational views of FIGS. 2 and 5, respectively.

FIG. 3

FIG. 1

FIG. 2

FIG. 6

FIG. 4

FIG. 5
